PANORAMIC RADIO RECEIVING SYSTEM

Marcel Wallace, New York, N. Y., assignor, by
direct and mesne assignments, to Panoramic
Radio Corporation, a corporation of New York

Application March 17, 1938, Serial No. 196,520
In France February 21, 1938

36 Claims. (Cl. 250—11)

My invention relates broadly to radio systems and more particularly to a panoramic system of radio reception.

One of the objects of my invention is to provide a signal receiving system for integrating the effects of a multiplicity of simultaneously received signals and rendering the signals thus received visible in a manner whereby the relative characteristics of the several receiver signals may be readily compared.

Another object of my invention is to provide means in a radio receiving system for visually comparing the relative field strength of a multiplicity of transmitting stations received simultaneously in any prescribed area.

Still another object of my invention is to provide means in a radio receiving system for observing the characteristics of a multiplicity of signals simultaneously received over a predetermined and continuous band of frequencies for determining all signals operative within that band and comparing their relative strength and difference of frequency.

A further object of my invention is to provide a receiving system equipped with visual and acoustical indicating means and operative to sweep a band of frequencies adjustable at will for determining the characteristics of signals simultaneously receivable in a given area over any selected band or bands of frequencies.

A still further object of my invention is to provide a radio receiving system capable of analyzing the characteristics of a multiplicity of signals receivable over several bands of frequencies of adjustable width.

Another object of my invention is to provide a signal receiving system which may be readily installed on a moving vehicle, ship or aircraft for visually imparting to the observer a panoramic conception of radio signals receivable in the geographical area with respect to which the vehicle, ship or aircraft is moving for providing the observer with a sense of security as to direction of movement of the vehicle, ship or aircraft and the location thereof with respect to a plurality of signalling stations.

Still another object of my invention is to provide a radio receiving system particularly adapted for operation on aircraft which will enable an observer to visually and aurally compare the characteristics of a plurality of simultaneously received signals to provide the pilot with accurate information for guiding the aircraft toward or away from or with respect to a multiplicity of

radio range beacons, broadcasting stations or other signalling stations.

A further object of my invention is to provide a receiving system particularly adaptable for operation on an aircraft in cooperation with a beam network system as set forth more fully in my Patents 1,802,688, dated April 28, 1931, for Beam network system; and 1,878,737, dated September 20, 1932, for Radio beacon system, by which the pilot of an aircraft may be informed of signalling conditions existing simultaneously at any given position on the airways.

A still further object of my invention is to provide a signal receiving system which is operative to visually indicate a plurality of signals in any definite region of a predetermined band of frequencies and consequently enable an observer to determine his position in relation to the sources of emitting energy, thereby providing a sense of security and improving the confidence and morale of the pilot and aircraft passengers who are often obliged to fly under conditions of poor visibility.

Another object of my invention is to provide that type of visual indicating system for aircraft piloting which is particularly efficient in indicating differences between parasitic signals or interfering sources of signal energy which have no function in a piloting system and the actual sources of signal energy which are to be depended upon for aircraft navigation, thus avoiding errors in piloting which have in the past resulted in grave consequences.

Still another object of my invention is to provide a signal receiving system for aircraft which is effective 360° around existing radio range beacon stations, thereby increasing the usefulness of radio range beacon stations in aircraft piloting which normally provide information for pilots only in restricted paths which are the equi-signal zones of the usual radio range system.

A further object of my invention is to provide a visual indicating system for aircraft navigation in which a similitude map of the geographical area over which a plane may fly may be correlated with the characteristics of signalling energy simultaneously receivable within the area defined by the limits of the similitude map for continuously informing the pilot of the geographical position of the aircraft.

A still further object of my invention is to provide a system of aircraft navigation in which the usefulness of the available frequency spectrum may be considerably increased by reason of the complete use of the band as a continuity

without the need of providing for wasteful gaps, and also by reason of the characteristics of the visual indicating system employed by my invention for effectively distinguishing and comparing the characteristics of emitted sources comprised on the whole of the band, and consequently on closely adjacent frequencies.

Another object of my invention is to provide a signal receiving system having means for periodically tuning the signal receiving system over predetermined bands of frequencies and synchronously operating the control circuits of a cathode ray oscillograph connected with the output of the signal receiving system for visually indicating the characteristics of the signalling energy simultaneously receivable over the bands of frequencies over which the receiving circuit is periodically tuned.

Still another object of my invention is to provide a panoramic radio compass system having visual indicating means operative in correlation to the radio compass system for visually indicating the angular relation of a mobile body carrying the radio compass system, with respect to the location of a plurality of stations whose signals are simultaneously received.

A further object of my invention is to provide a receiving system operative to visually reproduce a plurality of simultaneously received signals and compare the characteristics thereof in combination with aural receiving means, with means interconnected between said aural and visual means to identify the station which is being heard with one of the stations of a plurality of stations whose characteristics are visually observed.

Other and further objects of my invention reside in various combinations of circuits and instrumentalities and apparatus used in connection with the circuits of my invention, as set forth more fully in the specification hereinafter following by reference to the accompanying drawings in which:

Figure 1 is a diagrammatic view of one form of circuit embodying the principles of my invention; Fig. 2 illustrates characteristic curves showing the characteristics of the periodically varying tuning system employed in the circuit of my invention and the correlation of the automatic control circuits of the oscillograph employed in the receiving system; Fig. 3 is a typical diagram showing the wave form of a multiplicity of signals reproduced on the screen of the oscillograph of the panoramic receiver; Fig. 4 shows a circuit diagram of a panoramic receiver employing electronic means for periodically tuning over a band of frequencies and correlating the operation of the control circuits of the oscillograph used in connection with the receiving system; Fig. 5 illustrates in elevational view one form of condenser system which may be employed in the panoramic receiving system of my invention and in which the maximum to minimum capacity ratio of the condenser system may be adjusted; Fig. 6 is an end elevational view of the condenser system illustrated in Fig. 5; Fig. 7 is a fragmentary view of a modified form of adjustable condenser system which may be used in the panoramic receiver of my invention and illustrating another means of adjusting the maximum to minimum capacity ratio of the periodically operated tuning system; Fig. 8 illustrates a generator which can be used in connection with my invention for controlling one of the elements of the oscillograph in the panoramic system of my invention; Fig. 8a shows the characteristic curve obtainable from

the generator illustrated in Fig. 8; Fig. 9 is a schematic view showing the arrangement of a multiplicity of beacon stations with which the panoramic receiving system of my invention is adapted to coact; Fig. 10 is a plan view showing one manner of coordinating means for aligning with the screen of the oscillograph a similitude map of the area over which a mobile body equipped with the panoramic system of my invention moves; Fig. 11 illustrates a modified plan view of the screen of the oscillograph and similitude map operating in conjunction therewith, wherein both horizontal and vertical axes of the oscillograph are employed for indicating the position and character of transmitting stations operating simultaneously in the area within which the panoramic receiver is adapted to operate; Fig. 12 is a fragmentary side elevational view of the apparatus illustrated in Fig. 11; Fig. 13 illustrates a simplified wiring diagram of the panoramic radio receiver embodying my invention and showing the manner of periodically varying the tuning means of the receiver and correlating the operation of the control circuits of the oscillograph; Fig. 14 shows a modified method of varying the band of frequencies over the panoramic receiver which is periodically tuned and adjusting the position in the frequency spectrum with respect to which the receiver periodically operates; Fig. 15 shows a further modified arrangement of circuit whereby in addition to the adjustment or selection of the band over which the receiver periodically operates, I am enabled to control the width of the band which is periodically varied in the panoramic receiver of my invention; Fig. 16 illustrates a further modified arrangement of the periodic tuning means in which the adjustment of the position of the band over which the periodic tuning is effected may be selected by steps with respect to the entire frequency spectrum over which the receiver is designed to respond; Fig. 17 is a schematic circuit arrangement illustrating a composite panoramic receiver with means for simultaneously receiving both panoramic visual indication as well as aural indication of one of the stations visually indicated and also with means to show on the screen which one of the stations is being rendered audible; Fig. 18 shows an application of the panoramic receiver of my invention to a measuring instrument by which the frequency of a multiplicity of signalling stations over a predetermined frequency range may be determined by visual means; Figs. 19 and 20 are side, elevational and end views respectively of one arrangement of mechanically actuated switches for operating the control circuits of the oscillograph synchronously with the operation of the periodically operated tuning means of the panoramic receiver; Fig. 21 illustrates a method of reversing the phase of a radio compass receiver and synchronously controlling the operation of periodic tuning means and the operation of the control circuits of the oscillograph connected with the radio compass receiver; Fig. 22 illustrates a circuit arrangement whereby a set of the controlling elements of the oscillograph is periodically reversed in synchronism with the frequency variation of the receiver so as to obtain two sets of images on the screen of the oscillograph; Fig. 23 shows an arrangement for periodically switching from one radio frequency energy collecting circuit to another radio frequency energy collecting circuit in synchronism with the operation of control circuits of the oscillograph and the operation of the periodically operated

tuning means of the panoramic receiver; Fig. 24 illustrates a panoramic receiver in which the source of energy which operates the radio receiving system is also employed for operating the drive means for synchronously varying the control circuits of the oscillograph and the periodically operated tuning means of the receiver; Fig. 25 illustrates another form of generator which may be employed for obtaining the control potential for the oscillograph in the panoramic receiver; Fig. 26 illustrates characteristic curves showing the changes of control potential for the oscillograph as compared to the changes in capacity in the periodically operated tuning circuit of the panoramic receiver; Fig. 27 shows characteristic curves of control potential which may be obtained by modifying the shape of the armature and/or pole pieces shown in Fig. 25 so as to compensate for a non-linear frequency variation of the periodically tuning means of the panoramic receiver; Fig. 28 is a schematic diagram showing the manner of coordinating the special form of generator illustrated in Fig. 25 with the control circuits of the oscillograph whereby the characteristics of a part of the frequency band over which the panoramic receiver is periodically tuned are visually reproduced on one axis of the oscillograph and the other part of the frequency band is reproduced on the other axis of the oscillograph; Fig. 29 shows the time correlation between the variation of frequency of the periodically tuned receiver, variation of voltage of the controlling elements showing the time when this voltage is suppressed and the moments when the connections between two of the controlling elements of the oscillograph are changed; Fig. 30 shows one method of coordinating the movement of the direction finder antenna of a radio compass receiver with the mounting of the oscillograph connected with the circuits of a radio compass receiver for correlating the angular displacement of the oscillograph screen with respect to the angular movement of the direction finder antenna; Fig. 31a, Fig. 31b, Fig. 31c, Fig. 31d and Fig. 31e illustrate the visual indications reproducible on the screen of the oscillograph as the angular relation of the oscillograph screen and direction finder antenna is varied by some such correlation method as illustrated in Fig. 30; Fig. 32 illustrates a polar diagram of either a radio range system or of a phase-reversing antenna-loop receiving system, and schematically shows the manner of visually reproducing on the oscillograph screen the signalling energy as illustrated more particularly in Figs. 31a, 31b, 31c, 31d and 31e; Fig. 33 illustrates an example of the very large number of bearings which may be taken by an observer using the panoramic system of my invention over a predetermined course which number of bearings greatly exceeds the possibilities obtainable in existing systems; Fig. 34 is a schematic diagram showing a panoramic radio compass embodying the system of my invention; Fig. 35 is a fragmentary view showing the characteristic curves of one station receivable on the screen of the oscillograph of the panoramic radio compass as a plane equipped with the radio compass system of Fig. 34 swings to the right or left with respect to an emitting source; Fig. 36 shows the manner in which on course or off course signals are reproduced on the oscillograph screen of the panoramic radio compass receiver from signals of radio range beacons; Fig. 37 shows a multiple band panoramic receiver whereby two bands of frequencies of ad-

justable width appear on separate portions of the screen of the oscillograph; and Fig. 38 shows the arrangement of a series of marker beacon signals disseminated along a radio range equi-signal beam, each having different frequency characteristics so as to give continuous position indications to an observer flying along that beam and equipped with such a panoramic receiver.

My invention is directed to a panoramic radio receiving system. By the term "panoramic," I refer to the ability of a radio receiver to impart a simultaneous conception of all of the signals receivable in a given area for obtaining therefrom a sense of the relative position of the receiving station with respect to the sources of all of the signal emitters. In prior radio systems, such as the finding of signalling stations, information service, aerial navigation, guiding of planes and ships, etc., it has been necessary to be on the look-out over a wide band of frequencies in order to realize the existence of certain transmissions or for comparing these transmissions in amplitude as well as in frequency. With the ordinary radio receivers, one must tune these receivers successively on the frequencies of each of the stations to be received. The comparison of signals thus received is difficult.

In order to facilitate this comparison the combined use of a plurality of radio receivers has been proposed but this solution has little practical value and becomes still less so when it is necessary to receive simultaneously the signals for a large number of stations. This inconvenience is particularly grave in the case of aerial navigation when increase in weight is to be avoided. My invention accomplishes objects never heretofore obtained in the art by imparting to the observer at a receiving station equipped in accordance with my invention a sense of security with knowledge of the relative position of the receiving station with respect to all of the sources of signalling energy over a given frequency range in the vicinity of the receiving station.

My invention concerns a radio receiver for the simultaneous reception of a plurality of signals. An apparatus whose characteristic is that its instantaneous band pass which corresponds to its resonance curve, periodically moves in a continuous manner over a band of frequencies of a width adjustable according to the wish of the operator between definite tuning limits, so that the operator perceives simultaneously the signals emitted by a plurality of radio stations in the chosen band of frequencies. The radio receiver is combined with means giving for the chosen band of frequencies, over which the resonance curve of the set moves periodically, a visual representation of all the signals received at their respective amplitudes. The means of visual representation are constituted by a cathode ray oscillograph tube combined with a source of voltage and automatic means causing an alternate sweep of the screen of this cathode ray tube in synchronism with the periodical variation of the instantaneous band of reception of the frequency bands chosen.

According to another method of carrying out my invention, the width of the band frequencies covered by the periodical sweep can be varied by means modifying the maximum electric value of the tuning element which is submitted to the periodical variation corresponding to the alternating movement of the instantaneous band of reception. The invention concerns not only a radio receiver capable of giving a visual represen-

tation of a multiplicity of signals but also a system of aerial navigation characterized by a combination of a network of radio stations whose frequency is determined by their geographic position and of a mobile body such as an aircraft carrying such a receiver, said receiver producing visual indications of the frequencies received for enabling one to determine the position of the plane in relation to one or several of the transmitting stations. According to one characteristic of the invention, the system of visual indication can be combined with a set of geographic maps of the territory over which the aircraft flies. My invention also contemplates the synchronized control of a cathode ray oscillograph with means for periodically varying the frequency range of a receiving system for simultaneously observing the signals receivable in a given area over the frequency range over which the receiver is periodically tuned. I provide a special form of circuit for predetermining the range over which the receiver is periodically tuned so that the receiver may be variably tuned over any portion of a selected frequency range or over an entire frequency range at the will of the operator.

The invention includes circuits associated with the oscillograph by which my receiver can be used as a panoramic radio compass or panoramic direction finder, by this term being understood the ability of such a receiver to give simultaneous angular indication to a plurality of stations. In one of the applications of my invention to radio compasses, I provide means for coordinating the movement of the direction finder antenna with an oscillograph whereby a more definite visual indication is given of the relative position of the moving body and the signal emitters in the area surrounding the moving body.

My invention further contemplates means for visually indicating on the oscillograph screen the relative positions of simultaneously operating emitters in the vicinity of the receiving station on both horizontal and vertical axes of the oscillograph screen and thus enlarging the vision of the observer and increasing the sense of security of the observer at the receiving station. My invention is further characterized by the provision of means associated with the oscillograph tube for indicating on the oscillograph screen reverse images of the signals simultaneously emitted by the various transmitters in the vicinity of the receiving station for enabling the observer to more accurately judge the characteristics of each of the signals which are received. With such a receiver we can use special networks of transmitters which could indicate more accurately the position of the mobile body in relation to such special transmitters for example a beam network system such as described in my United States Patents 1,802,683, granted April 28, 1931, for Beam network system; 1,878,737, granted September 20, 1932, for Radio beacon system; 2,063,534, granted December 8, 1936, for Automatic piloting system; and as set forth in my copending application Serial No. 102,798, filed September 26, 1936, for Position indicator. By this method of reception we are enabled to use circuits of extreme selectivity such as can be obtained with crystal filters and the like, and this affords the possibility of using a much larger number of stations within a given frequency band.

In the form of my invention wherein a graphic representation of the characteristics of the received signals is obtained visually on both the vertical and horizontal axes of the cathode ray

screen, I employ an arrangement on the central drive shaft extending from the motor that drives the tuning system for periodically tuning the signal receiving circuit which includes in addition to the commutator device heretofore explained in connection with the operation of the control circuit of the oscillograph, a sweep voltage special wave form generator and in association therewith a cam actuated mechanism for alternately reversing the connection of sets of deflecting plates with respect to the signal receiving circuit; that is, from vertical to horizontal and vice-versa. The sweep voltage special wave form generator reverses the direction of current supplied to the control circuit of the cathode ray oscillograph every 90° of the rotation. The sweep voltage special wave form generator is synchronized with the rotation of the rotors so that the minimum voltage occurs at the moment when these rotors are either corresponding to minimum capacities or maximum capacities of the rotating condensers. The commutator serves to periodically by-pass the output of the generator so that for 180° of the tuning range there is no energy impressed upon the control circuit of the oscillograph. The cam arrangement closes or opens a reversing switch for every 90° rotation of the shaft corresponding to the points of minimum and maximum voltage of the said sweep voltage special wave form generator. It can be seen that during 90° rotation, the signals received on one-half of the tuning range of the rotating condenser will be seen on one set of plates, whether vertical or horizontal, and in the next half of the tuning range on the other set of plates so that the visual representation on the screen of the oscillograph will show the stations comprised between frequencies F_0 to F_1 vertically disposed, and the stations comprised between F_1 and F_2 horizontally disposed. This results in a broad visual path over which numbers of simultaneously received frequencies may be observed either on the horizontal axis or on the vertical axis of the screen of the oscillograph. Such an arrangement also enables one frequency band to be scanned and observed on one axis of the screen of the cathode ray tube and a different frequency band scanned and the frequencies being received thereover observed on the other axis of the screen of the cathode ray tube.

In carrying out my invention, I employ various forms of tuning means in the signal receiving circuits as, for example, rotary condensers having laterally adjustable stator plates and wherein the position of the laterally adjustable stator plates with respect to the rotor plates is selectively adjusted with respect to the periodically moving rotor plates. I may also employ means for varying the transverse special relation of the stator plates for adjusting the capacity relationship with respect to the periodically driven rotor plates. Either of these methods and other methods may be employed for controlling the frequency range over which the periodically controlled tuning system is adjustable. The system of my invention is particularly adapted for selective aural reception of any one of a plurality of signals visually received with means for identifying the particular signal received. That is to say, a particular signal may be received aurally while a multiplicity of signals are being received visually and the wave forms of the emitted frequencies over the band of frequencies over which the receiving system is periodically tuned readily observed.

The system of my invention provides visual indicating means which quickly informs the observer as to the relative position of the receiving station with respect to the sources of signalling energy which are being simultaneously received. The indication provided on the cathode ray oscillograph screen indicates the sources of signalling energy either to the right or left of the receiving station or forward or in the rear of the receiving station. The indication is given by the form of the received signal which appears both above and below either of the axes of the screen and showing by their relative amplitudes the relative position of the receiving station with respect to the emitting sources.

My invention also contemplates the operation of a panoramic receiver over a multiple number of bands of frequencies which may be seen simultaneously over different portions of the screen of the oscillograph, that is, the observer may be informed as to frequencies emitted in the long wave band and be simultaneously informed as to frequencies emitted in the short wave band.

The panoramic radio reception applied to radio compasses adds to these the advantage of permitting instantaneous information as to the direction to a plurality of stations. It eliminates the necessity of tuning the radio for each station with consequent loss of time and false indications. Due to the high speed of the plane, when the stations on which observations are being made are quite near, when the most accurate information must be had, it is absolutely necessary to obtain the direction towards several stations simultaneously in order to be of real use.

Many combinations of antennas are possible. The method used is to obtain two different reception patterns containing the information required and applying each pattern, one on each side of the median line of the screen. These patterns can be used by either switching from one type of antenna to another type or by the use of two antennas used separately or in an additive or subtractive manner. One preferred method is the use of two directional loops forming an angle and switching them in the circuit in an alternating fashion, throwing the images formed by one loop on one side of the median line, and the images from the other loop on the other side of the median line, symmetrically opposed. By comparing each signal with its opposite image, produced by the other loop, the observer notes whether these signals are equal, in this case meaning that the loop is oriented in an equi-potential zone, or whether one is stronger than the other, thus showing the observer which of the stations are to the right or to the left.

The same result can be obtained with the use of a combination of a non-directional antenna and a loop, used simultaneously but with means to turn the phase of the loop by 180° for every alternating horizontal sweep.

When using the system in reference to a similitude map of the area over which a mobile body operates, either a two dimensional gradual frequency coverage of a territory or a one dimensional gradual variation may be utilized. In the latter case a simple distance calibrated chart can be used instead of a two dimensional map. Assuming that a radio range beacon, such as is used today, sends a signal directed from New York to Philadelphia and that on this beam there is located every few miles a marker of a frequency which varies in frequency as a func-

tion proportional to distance from a predetermined point of origin. If, for example, the frequency band periodically covered is adjusted so as to reproduce on the screen four such markers, and a similitude map made to the size of the screen is used, the navigation of the aircraft is greatly simplified. It is clear that as the craft approaches one beacon, the visual indication will increase in amplitude as the other over which the craft has passed will decrease in amplitude. The passage over each marker on the territory flown may be correlated on the similitude map, on which each marker is indicated, so that as the last marker is passed and the tuning of the receiver is readjusted to take in the markers following, the map may be simultaneously turned to indicate the route following. In this arrangement the reference lines would all be simply vertical lines, as only one distance coordinate would be used instead of two.

My invention facilitates navigation of a mobile body along narrow passages, sometimes long and winding, under conditions of poor visibility such as mountain passes, landing fields, etc. With such panoramic receiver continuously sweeping a band of frequencies assigned for collision prevention, an observer will be given adequate warning which can be simultaneously audible and visual of approaching danger by receipt of specially created warning signals which may come from one or a plurality of danger spots.

Another object is to avoid collisions of moving craft, between themselves, and with dangerous obstacles.

Dangerous passes or narrow passes, such as mountains, landing fields, etc., may be marked with a series of stations, preferably on two different and adjacent frequencies so as to create an equi-potential path along the route desired. In general, very low power is needed, varying between 10-100 watts when short waves are used. As the increase of field strength from a station is inversely proportional to the square of the distance and when quite near approaching the cube of the distance, it can be seen that any station will give a substantial signal providing one is near enough. The power is so adjusted as to create an equi-potential zone between, for example, F_1 F_2 . The pilot will watch for the two signals F_1 and F_2 and will keep them of about equal amplitude. Stations are located in the dangerous spots, and the pilot can see and hear at once when he approaches one of these spots and may steer away accordingly. Danger spots can be indicated always by certain frequencies which are assigned to give collision warnings. All moving craft could emit a signal on a given frequency in that band, which frequency can vary according to the position of the craft, and the power of the signal may be determined by its size and speed, enabling other craft to steer away and out of danger.

My invention also contemplates circuits which combine the ability of the observer to listen to any selected frequency and see the relation thereof visually with respect to other simultaneously received signals.

For portable installations where the source of energy is a battery, I may employ for the high voltages required by the tube elements, a small generator and the shaft of this will serve for the rotation of the tuning condensers as well as for the source of synchronized sweep voltage.

The weight of transformers and additional motor is thus saved.

The whole apparatus can be built very compactly and carried on board of plane or ship where it can serve many purposes.

By periodically tuning a certain part of the frequency spectrum, for example, the one containing the radio range beacons, the observer can at once see all the signals which can be received at that moment in that particular position of the plane. As each of these beacons sends periodically two signals at a certain angle to each other, these signals periodically vary in amplitude according to which one of the two is received.

If the receiver be on the equi-signal zones where the signals are received with equal strength, the two signals will appear of the same amplitude. If the receiver is on a "null" zone for one of the beams, the observer will instantly recognize this by the periodical complete disappearance of the signal. If the receiver is in an intermediary zone, the observer will be able to recognize this also by the periodical flicker of the signal.

I am thus enabled to increase the usefulness of existing radio range beacons. Also the possibility of comparing the variation of the signal strength of several radio ranges at the same time has very great advantages. The observer can also recognize when a plane is crossing various beams such as markers determining approaches to cities or airports, and when the plane passes over the "silence cone" of any station, by the sudden disappearance and reappearance of a very powerful signal.

With such a receiver, it becomes unnecessary to carry several receivers for various purposes, such as heretofore suggested, and it also becomes unnecessary to use a single frequency for certain purposes, such as in marker beacons, etc.

Referring in detail to Fig. 1 of the drawings, I have shown a superheterodyne type of receiver including four stages of circuits arranged according to the usual method in which there is a detector and oscillator stage combined in the tube 12 following by an intermediate frequency amplifier stage comprising tube 29 followed by a detector and the first audio frequency amplifier stage including tube 32 and the final audio frequency amplifier stage including tube 45. This final stage is connected with means for aural reproduction such as a loud speaker 50. The apparatus is energized from a source of alternating current 51 with the aid of rectifiers 52 and 53.

In this diagram the antenna 10 is inductively coupled with the first tuned circuit whose tuning elements are constituted by the variable condensers 1, 3 and 5, this circuit being connected to the control grid 11 of the tube 12. The local oscillations for the conversion of the frequency are generated in the usual manner in a circuit whose tuning elements are constituted by the variable condensers 2, 4 and 6, this circuit being connected to the grid 13 of the tube 12. The width of the band of frequencies covered by the periodic sweep is made variable by means modifying the maximum to minimum capacity ratio of the tuning element which is subjected to the periodical variation corresponding to this periodic displacement.

The variable condensers 3 and 4 are provided with rotors which can turn fully 360°. The two rotors which may be connected on the same shaft 75

are rotated by the motor 18 the power supply to which being controlled by a switch 20. This motor can be advantageously the same as the one generating the electric current usually used on board of a plane. The limits of the frequency spectrum which can be received by this apparatus can be modified on one hand with the aid of the variable condensers 1 and 2, each of these being connected in parallel with one of the rotating condensers 3 and 4, and on the other hand with the aid of the variable condensers 5 and 6 which are connected in series respectively with each of the rotating condensers 3 and 4.

15 The resultant minimum capacity of a tuned circuit which includes the tuning elements 1, 3 and 5, can be modified with the aid of variable condenser 1 for a given position of condensers 3 and 5 corresponding to minimum capacity for these condensers.

The continuous rotation of the condensers 3 and 4 which are driven by the motor 18 gives a variation of capacity which is represented by the lines *a* and *a'* of Fig. 2 for a complete 20 revolution of the rotors. In this drawing the lines *a* and *a'* are straight corresponding to a straight line capacity variation for these condensers. This does not mean that my invention requires such condensers, for on the contrary, other forms of variation may be preferred for special uses.

25 The maximum capacity proportional to ordinate point *M*, is obtained when these rotors have entered completely between the fixed plates of the stator.

The periodical displacement of the instantaneous band pass, which is determined by the curve of resonance of the receiver, is obtained by the periodical variation of capacity of condensers 3 and 4 between a value which is practically zero and a maximum and vice versa, due to the continuous rotation of the rotors. The width of the band of frequencies thus periodically covered can be adjusted by tuning the two variable condensers 5 and 6 whose rotors are 30 ganged together.

If the maximum capacity *C* of the rotating condensers 3 and 4 is equivalent to that of each of the elements 5 and 6, which for example have their rotors completely enmeshed with the stator plates, the maximum capacity resulting for each of the groups of the series 3-5 and 4-6 is 35 equal to *C/2*.

For any other position of the rotors of condensers 5 and 6 the maximum capacity of each group 3-5 and 4-6 becomes less than *C/2*.

I employ various methods for adjusting the maximum capacity of the groups of elements 3-5 and 4-6 and consequently of the width of the frequency band periodically covered by the band pass of the set, at each turn of the rotor blades of condensers 3 and 4 rotated by motor 18. Fig. 1 illustrates one arrangement and Figs. 13 to 16 show other arrangements. If the maximum capacity of the variable condensers 1 and 2 is *C'*, it is easy to understand that the origin or lower limit of the band of frequencies periodically swept can occupy, in a total band of frequencies which can be received by my apparatus, any position comprised between the tuning frequency corresponding to the minimum capacity of condensers 1 and 2 and the tuning frequency corresponding to *C'*.

As illustrated in the drawings, a cathode ray oscillograph tube 17 is combined with the radio

receiver to give a visual representation in the chosen band of frequencies of all the signals simultaneously received and to show the respective amplitudes of the signals.

The horizontal deviations of the cathode ray beam between the deflecting plates 9 of tube 11 are produced in exact synchronism and in phase with the periodical displacement of the instantaneous band pass. For this purpose, one of the plates 9 is electrically connected to the insulated side of condenser 21 which can be charged by a source of voltage, for example, from point 38 of the source of voltage of the radio receiver. The resistance 22 and the capacity 21 are so chosen that the charge of condenser 21 is incomplete during one-half rotation of condensers 3 and 4. Condenser 21 is connected, either directly or through an amplifier, (as shown in Fig. 13), to deflecting plate 9 and also through a resistance 23 to a brush 26 on commutator 24, 25. The commutator 24, 25 is mounted on the shaft 19 of motor 18 and permits the sudden discharge through resistance 23, as indicated at *d* in Fig. 2 of condenser 21, by means of the grounding brush 27, connected to shaft 19, during each half rotation of motor 18, when the metal part 24 of the commutator 24, 25 is in contact with the brush 26.

As soon as the insulated half 25 of the commutator 24, 25 comes under the brush 26 during another half turn of shaft 19, the condenser 21 is insulated and can be recharged through the resistance 22. In order to obtain the necessary synchronism between the successive charges of the condenser 21 and the periodical displacements of the instantaneous band pass of the set, it is necessary to time the passage of the brush 26 over the separating line between the halves 24 and 25 of the commutator 24, 25, simultaneously with the moment when capacities of the rotating condensers 3 and 4 pass either through minimum or through maximum.

In Fig. 2, the line *b* represents the variation of voltage between the ends of the condenser 21 as it charges through the resistance 22. This line *b* is situated underneath the line *a* which represents the variation of capacities of condensers 3 and 4. For simplicity of understanding Fig. 2, I have shown straight lines for both capacity as well as the variation of sweeping voltage. This variation does not have to be linear, for in most applications of my invention I require equal spacing between two given frequencies on any part of the image on the screens 30 of the oscillosograph 17 and this result can be obtained by varying the curve representing the variation of either variable condenser or of the sweeping voltage or of both. Such a relationship of voltage and variation of frequency is shown in Fig. 27.

This arrangement causes a horizontal sweep on the screen 30 of the cathode ray oscillosograph 17 according to the line A—B of Fig. 3.

The signal rectified by the detector tube 32, Fig. 1, is applied on deflecting plate 15 which produces a vertical deviation of the cathode ray beam of the oscillosograph 17. A variation of the voltage of condenser 21 is visually reproduced on the screen 30 of the oscillosograph 17 as a periodical horizontal movement of the light spot while for each signal detected by tube 32 during the rotation of condensers 3 and 4, a vertical displacement of this light spot is produced parallel to the axis *y*—*y* of Fig. 3 and of a height proportional to the intensity of the signal. The vertical displacements will be seen on the screen

30 in different positions between A and B corresponding to the frequencies of the signals received. If the speed of rotation of motor 18 is sufficient, the eye will perceive, due to the persistence of visual impressions and due to the persistence of the screen 30 of the cathode ray oscillosograph 17, the continuous wave forms of the simultaneously received signals. A continuous curve is reproduced on screen 30 showing a certain number of maxima E, F, G, higher or lower according to the field intensity of the stations, or according to their proximity to the receiver and the distances between E, F, G, corresponding to the difference of frequencies between the sending stations.

Due to these different characteristics, the operator can first modify on the screen 30 of oscillosograph tube 17 the position of the band of frequencies desired by tuning the capacities 1 and 2; it is very easy to analyze in its details any region of a certain band of frequencies, a necessity which may be present when the observer must follow the approach to a given station. If more details must be had of a relatively narrow band this can be obtained in either of two ways, either by variation of the horizontal sweep voltage as obtainable by the use of the sweep voltage amplifier shown in Fig. 13, or the variations of the tuning capacities.

The second method is preferable when a wide frequency band must be explored. The capacities 1 and 2 are tuned for bringing the frequency region desired substantially into the center of the screen and then the maximum capacities of the groups of condensers in series 3—5 and 4—6 may be reduced by moving condensers 5 and 6. This operation causes a reduction of the band of frequencies periodically covered which appears as a lateral enlargement of the curve of visual representation on the screen 30 of the oscillosograph shown in Fig. 3, because the horizontal deviation of the spot remains constant for this reduced band of frequencies, that is, line *b* in Fig. 2.

If the receiver which causes the indication F, shown in Fig. 3, is on board of an aircraft approaching a powerful station, the observer sees on the screen 30 the signal corresponding to this station going up or growing and will see it go down or decrease as and when the plane travels away from the station. Low powered stations give generally a very marked effect. They may be entirely inaudible and consequently will not be seen on the screen at a distance of a few miles and then suddenly appear and increase at a very high speed as the plane is approaching and will then go down and disappear just as fast. Powerful stations will be seen for a much longer time or greater distances and, of course, the variation as the plane approaches or travels away from such stations will appear less marked. By observing simultaneously the signals produced by several stations, the observer obtains precise information as to the position of the plane and as to the direction of movement of the plane.

Many modifications of the apparatus hereinabove described may be made without departing from the spirit of my invention. For example, the combination of a radio receiver according to my invention with means to periodically displace the band pass can be suppressed if the navigator wishes to hear through the loud speaker 50 certain stations, for example, those giving meteorologic information or time signals, etc. In order to do this it is sufficient to stop the motor

18 by means of the switch 20 or to provide a clutch system to disconnect the condensers 3 and 4 which can then be adjusted by hand or cutting out the groups of condensers 3, 5, and 4-6 by means of a double pole single throw switch 55.

Fig. 13 represents the simplest diagram of my invention in which a receiving circuit is tuned by means of condenser 3 whose rotor is under continuous rotation by means of shaft 19 connecting it to motor 18. Such a circuit will periodically be tuned over a certain band of frequencies with definite and invariable limits. One amplifier is shown for controlling the sweep voltage applied to plate 9 for determining the length of the line produced on the screen of the oscillograph, and another amplifier is shown for controlling the amplitude of the visual signals shown on that screen as applied to deflecting plate 15.

Fig. 14 shows another form of the circuit in which another condenser 1 is in parallel relation with rotating condenser 3. Such an arrangement allows a shift of the band of periodically varying frequencies between certain limits which depend on the position of condenser 1.

Fig. 15 shows a more complete arrangement whereby the rotating condenser 3 is connected in series with a variable condenser 5 and the two of them being connected in parallel relation to condenser 1. Such an arrangement permits the narrowing or enlargement of the band of frequencies over which the set is periodically tuned and the positioning of this band in any point of a wider band which is determined by the variation of condenser 1.

Fig. 16 represents a system somewhat similar to Fig. 15 in which the condenser 5 has been replaced by condensers 5a, 5b or 5c, one of which can be selected and connected into circuit by means of a rotary or similar switch 55a. The switch in the example chosen in Fig. 16 has five positions. In position *m*, the condenser 3 is in parallel with condenser 1, thus reproducing the conditions obtained in Fig. 14. In positions *a*, *b* and *c*, condensers 5a, 5b or 5c are successively connected. These condensers are of different capacities and in this manner the same conditions as those contained in Fig. 15 are obtained, corresponding to definite settings of variable condenser 5. In position *d* the rotating condenser 3 is out of circuit and the set becomes a normally tuned set on a single and unvarying frequency.

The displacement of the band of instantaneous reception can also be effected by many different other methods. The displacement may be obtained here mechanically with the aid of a tuning element such as a condenser or a variometer continuously rotating around its axis so as to pass through its maximum and minimum values several times per second. This displacement can also be obtained by purely electrical methods as illustrated in Fig. 4, without the use of any moving parts.

In the arrangement shown in Fig. 4, I show a receiving circuit capable of giving visual representation of the various frequencies received over a certain band of frequencies in which there are no moving parts and the means for periodically tuning the receiving circuit as well as the sweep voltage of the cathode ray oscillograph is produced entirely by electrical means. Such a receiver includes a receiving circuit tuned by means of variable condenser 1c. One side of this circuit is connected to a tube 180 in such a way as to apply the capacities of this tube to the tuned

5 circuit. These capacities are rendered variable by impressing upon the tube 180 a periodical voltage variation which is produced by tube 181. The tube 181 is connected as a saw tooth oscillator whose frequency of oscillation is determined by the source of voltage applied and by the capacity of the condenser 182. Before impressing this saw tooth voltage on tube 180, this voltage is first amplified through tube 185. The output of this amplifier passes through a potentiometer device 183 which permits feeding into the tube 180, an adjustable potential, which according to its magnitude causes smaller or wider variation of frequency in the receiving circuit of the tube 12. The same output from the amplifier tube 185 is used for creating the sweep of the cathode ray beam along one set of deflecting elements 9. The output of the tube 12 is amplified in the tube 184 and the output of this tube is applied to the other set 15 of the deflecting elements of the oscillograph 17. Condenser 1c permits the selection of any frequencies around which a periodic variation is to be obtained according to the amplitude of the saw tooth potential applied on the tube 180. This band can be widened to the point desired. By using the same saw tooth voltage for both frequency variation and sweep voltage an absolute synchronism is obtained. I may also affect the frequency by the variation of inductance produced through the circulation of an alternating current in a circuit containing a magnetic core.

In the example described above, the groups of the variable condensers in series 3-4, 3-6, 35 can be replaced each by only one condenser such as represented in Figs. 5, 6 and 7. The apparatus in Figs. 5 and 6 is essentially composed of a group of plates 33 which are rotated by shaft 19 under the action of the motor 18 and of a group of plates 35 which may be adjusted parallel to the planes of the rotor plates 33. The group of plates 35 can be interleaved between the plates 33 by an adjustable amount so as to modify the maximum capacities which can be attained by the condenser during each turn of the plates 33. The linear displacement of the plates 35 is obtained for example, by movement of the cam 36 against the action of the springs 37.

Rotating condenser of Fig. 7, which is to be used mostly for reception of ultra-short waves, is illustrated with but one rotor plate 56 interleaved between two stator plates 57, 58, which may be adjusted in the directions f_1 , f_2 , normal to the plane of the plate 56. The variation of 55 maximum capacity of this condenser is obtained by rotating the control member 59, which rotates threaded shaft 59a, which engages the threaded members 57₁ and 58₁, which carry the plates 57, 58. The shaft 59a has two threaded portions 59₁ and 59₂ which are reversed in relation to each other and cause symmetrical displacement of the plates 57 and 58 in relation to the rotor plate 56.

In the circuit of Fig. 1, the voltage variation 65 necessary for the horizontal sweep of the cathode ray tube 17 is produced by the charge and the discharge of the condenser 21. There are, however, many other methods (electronic oscillators, etc.) for obtaining the pulsating current required for the horizontal sweep of the screen 30. The condenser 21 and the resistance 22 may be replaced by the electromagnetic alternating current generators represented in Fig. 8 and Fig. 25.

The generator shown in Fig. 8 includes a rotor 70 comprising two portions of a spiral 62, 63, sym-

metrically opposed. The rotor is journaled for rotation between the pole pieces 65 and 66 of the magnetic core 70, which carries magnetic winding 70a. The spirals 62 and 63 have between themselves two diametrically extending flat portions 64. When the rotor 61 rotates between the pole pieces 65 and 66 of the magnetic winding 70a, a saw tooth current is produced in conductor 67 according to the characteristic curve 71 shown in Fig. 8a, which is applied after proper amplification indicated at 69 to the deflecting plate 9 producing a horizontal deviation of the cathode ray beam in tube 17. The rotor 61 of this generator may be advantageously mounted on the shaft 19 of the motor 18 acting upon the variable condensers 3 and 4.

Fig. 25 shows a similar generator in which the comparative parts are indicated by the same reference characters having subscripts, that is, generator 25 includes a rotor 61a journaled between pole pieces 65a and 66a of the magnetic core 70b containing winding 70a. The rotor 61a is shaped to produce the current of the characteristic shown in Fig. 26. It can be seen that the variation of voltage between minimum and maximum limits occurs between zero and 90° rotation of armature 61a which variation occurs twice as fast as variation of capacity of condensers 3-4. Condensers 3-4 and armature 61a must be linked together by a gearing or otherwise so that armature 61a moves at half the speed as that of condensers 3-4. By such a combination, the use of commutator 24-25 becomes unnecessary and furthermore, the sweep on screen 30 of oscillograph 17 will occur in both directions of the movement of the cathode ray beam so that double the number of images are reproduced for the same number of rotations of condensers 3 and 4. In a special application of a compass such as described in Fig. 28, the condensers 3-4 turn at the same speed as the rotor 61a as will be pointed out hereinafter.

The visual representation of a plurality of signals to be used for aerial navigation offers particularly important advantages when it is used in combination with a network of special stations arranged to cover a large geographical area as set forth in my Patent 1,802,688, *supra*.

According to the invention, such a network is constituted in groups of parallel beams, to each of which a certain band of frequencies is assigned, the frequency of any beacon being a function of one of the geographic co-ordinates and varying progressively by increments proportional to variation of geographical distance, latitude and longitude. One of the groups may be directed north-south and another group directed east-west.

Fig. 9 shows a portion of a territory over which stations 101-102 . . . 109 are arranged which for the purpose of clarification are regularly disposed. Assuming that one of these stations emits four lobes of radio frequency energy, two directed north and south and the other two east and west, each of the two lobes in bands of frequencies assigned to such directions. All the stations on the same longitude are sending north-south signals on the same frequency. The bands will successively be recognized by the series of frequencies $F_1, F_2, F_3, \dots, F_n$ which are comprised, for example, within the continuous frequency band of 60,000 and 60,500 kilocycles.

In the band of frequencies assigned to the direction east-west, the beam stations of the same latitude situated in one given horizontal band

send east to west signals of the same frequency and these bands will be recognizable by the series of frequencies $F'_1, F'_2, F'_3, \dots, F'_n$ comprised, for example, within the continuous frequency band of 60,500 and 61,000 kilocycles. For each station, the two frequencies F_n and F'_n are determined according to a definite function and represent consequently the geographic coordinates of that station with respect to two predetermined reference lines. The very high frequencies which can be used for such a beam network permit the use of low power (non-modulated) transmitters consisting of a pair of equally powered oscillators which are pre-tuned to the frequencies F_n and F'_n with very small and similar directive antenna arrays at 90° to each other; these can be installed from place to place on suitable supports and operate automatically and without any special care or attention so as to cover a relatively large territory from two reference axes. Such a system of beams is characterized by two series of equi-potential zones 90, 91, 92, 93, 94, 95 over which the received signals of determined frequencies are of substantially equal field strength. The decrease in field strength of a signal received by a pilot who travels away from the station 102 in the direction f_1 is up to a certain point compensated by the increase in field strength of the signal of the same frequency emitted by station 103 which the pilot is approaching.

The equi-potential effect cannot be perfect; a certain point V on the territory covered by this network is under the influence of a very complex electromagnetic field which can be translated by a plurality of visual signals on the screen 30 in which one or two will predominate.

If the power of the two oscillators F_n and F'_n of each station is equal and their vector diagrams are identical but at 90° to each other, the field intensity ratio of the two signals will be proportional to their vector ratio in that given point. This vector ratio changes with the direction to the station and, consequently, this direction can be known by knowing the field strength ratio of the two signals. The vector diagrams of the stations can thus be chosen as to give precise information for 360° around each station.

In the panoramic receiver, all signals resulting from the north-south beams (F_1, F_2, F_3 , etc.) will appear to the left of the vertical median line $y-y$ disseminated to the right and to the left of the predominating signals. A second series of signals resulting from beams east-west F'_1, F'_2 , etc. will appear to the right side of the median line $y-y$, the various signals being disseminated to one side and the other of the predominating signals. Certain parts of the territory covered by such a beam network, such as cities, airports, mountain passes, present a great importance from the standpoint of navigation to the points having less importance. According to the importance of each point such as T, Fig. 9, a larger or smaller number of such stations would be installed, each transmitting two frequencies F_n and F'_n , predetermined by the geographical position of that point. The stations will emit perpendicular beams which coact with the others transmitted in the same direction. They do not "interfere" with each other, but on the contrary, the greater the number of such stations, the more uniform will be the gradient.

The pilot having on board a receiver such as described, sweeping continuously the band of 60 to 61 megacycles, can immediately see the fre-

quencies which predominate in the region over which he flies and he can thus determine instantly the position of the station over which or near which he flies. The screen 30 of the oscilloscope 17 is divided by horizontal and vertical lines. At the left of the median line $y-y$, as shown in Fig. 10, the pilot can see the beams north-south and on the right side the beams east-west, whereas the horizontal lines permit him to judge the field intensity ratio of the signals received, and consequently the direction or azimuth of the station, the location of which was determined as seen above, by its two frequencies.

Beam network of Fig. 9 is given as an example which is non-limiting; it is not necessary that the transmitting stations should be equi-distant nor of equal power. The general principle of this system of navigation is to assign to any point of a territory thus covered, two characteristic frequencies, each corresponding to one of the geographic coordinates of that point. Any station which must be installed in any point must consequently emit two beams on these two predetermined frequencies which will thus identify its position.

With a radio receiver such as described, the position of the observer on board of a plane can be determined still easier by an arrangement combining the topographic representation of that territory with the image of the navigational signals coming from the different stations which is obtained on the screen 30 of the cathode ray tube 17. In order to accomplish this, the radio receiver combines the cathode ray tube 17 with a map or image in similitude of the region which is covered which shows instantaneously the position of the observer in this region. Figs. 10, and 11 and 12, represent two forms of my invention. In Fig. 10, a film or chart 73 is carried by reels 74, 75 which can be rotated by knobs 74', 75'. This film or chart contains a succession of maps or topographical representations 79 of the regions or country to be covered by the mobile body. Each of these topographic maps, containing all the details interesting the observer, can be placed by manipulating the knobs 74' and 75' in a fixed frame 78 adjacent the screen 30. The frame 78 is divided in squares 82, the vertical lines of which are formed by prolonging the vertical lines marked on the left half of the screen 30 of the cathode ray tube 17, whereas the horizontal lines of these squares 82 are obtained by the angular extension of the vertical lines from the second half on the right side of the screen 30. The observer who will see a plurality of signals of adjacent frequencies passing through a maximum on the left side of the screen, corresponding to signals north-south, will follow the vertical line on map 79. For the signals on the right side of the screen, corresponding to beams east-west, the observer will follow the line which becomes horizontal on this map 79 and the position of the nearest station will be determined thereon by the intersection of these lines. The prolongation of the vertical lines from the left and those on the right half of the screen 30 is visualized by means of a panel 77 mounted on the face of the screen and divided by a conventional number of equi-distant lines which can be graduated either empirically or in distance units corresponding to the scale of the chart used. In the example of Fig. 10, the vertical lines are illustrated as falling within the range 0, 10, 20, 30, 40 and horizontal lines for indicating amplitude ratios, in the range 0, 25, 75

50, 75, 100. This panel 77 has a rectangular or square perforation within the frame 78 under the left half of the screen so as to permit the placing in its correct position of that part of the film or band 73 which bears the topographic image 79 of the territory covered. This image is also divided in vertical bands 80 and horizontal bands 81, at each of which a predetermined band of frequency is allotted. These bands 80 and 81 correspond in distance to the vertical successive lines marked on the screen 30. The topographic images are reduced to a scale corresponding to the band width of the frequency sweep of the receiver, or vice versa.

15 In Figs. 11 and 12, I have shown an arrangement in which the similitude map may be employed directly over the screen of the oscilloscope. The images resulting from the north-south beams are reproduced on a horizontal axis of the cathode ray tube and the signals coming from the beams extending east-west are alternately reproduced with respect to the aforesaid images on the vertical axis of the tube. Both images are observed simultaneously. In this case, 20 I may employ a map of greater size directly on the face of the oscilloscope.

25 In Figs. 11 and 12, I have shown the reels which carry the band 73a at 74a and 75a respectively, controlled by the knobs 74'a and 75'a. 30 That is to say, the corresponding parts in the modified arrangement of Figs. 11 and 12, and indicated by corresponding reference characters but with the letter 'a' added thereto.

One axis of the screen 30 of the cathode ray 35 oscilloscope 17 covers a certain band of frequencies and the transverse axis covers another band of frequencies. I accomplish this by an arrangement shown in Fig. 28 with reference to the curves of Fig. 29. A generator such as previously described in Fig. 25, capable of producing a substantially straight line voltage variation for each rotation of 90° is used, so that the output appears like a zigzag line e—e', Fig. 29. This voltage passes through a minimum and maximum and returns to a minimum during 180° rotation of a shaft 19 to which condensers 3 and 4 are attached and during which such condensers pass from minimum to maximum only once. One side of this generator is connected to the ground of the receiver and the other side is connected to the commutator 24, 25, such as described in Fig. 1, but without a resistor arrangement. During a one-half rotation of the shaft 19, the receiver will be tuned between certain limits, such as F₀—F₁—F₂. By means of the switch arms 141, 142, and coacting contacts 143, 144, 145, the frequencies between F₀ and F₁ can be reproduced on one axis of the oscilloscope 17 and on the other axis the frequencies between F₁ and F₂ may be reproduced. This is done with the aid of the cam 146 which operates upon the switch arms 141 and 142 at every rotation of 90°, keeping the switch arm 141 connected to contact 144 and switch arm 142 connected to contact 145 during one quarter rotation which corresponds to line e and line V in Fig. 29, and releasing these switch arms so that the switch arm 141 touches contact 143 and switch arm 142 connects with contact 144 within the next 90° during the portion e' and H. V and H represent here the time period when the signals appear on the vertical axis or when they appear on the horizontal axis of the screen 30. During the next 180° rotation the generator voltage is grounded through commutator 24, 25 and this 40 45 50 55 60 65 70

portion is represented by straight lines Z of Fig. 29. This is a suppression period of the voltages which would have otherwise been established according to dotted lines e and e' above the suppressed zone. In the first position the output of the receiver corresponding to frequencies F_0 and F_1 is applied to the deflecting plate 15, while the sweep voltage is applied to deflecting plate 9. In the second position, the output of the receiver corresponds to frequencies F_1 — F_2 and is applied to deflecting plate 9, while the sweeping voltage is applied to deflecting plate 15. I prefer to use such an arrangement in connection with a beam network system which is using a band of frequencies F_0 to F_2 in which the frequencies F_0 to F_1 are used to determine one set of geographic coordinates, whereas frequencies F_1 to F_2 are used to determine the other set of geographic coordinates perpendicular to the first set.

Fig. 11 represents, as heretofore noted, an arrangement of the screen 30 of the oscillograph 17 in combination with a topographical representation of the area covered. On one axis of the screen corresponding to the abscissa of the co-ordinate system the frequencies F_0 to F_1 are visually reproduced and on the other axis corresponding to the ordinate the frequencies F_1 to F_2 are reproduced. A plurality of signals on these axes indicate a plurality of stations corresponding to the beams which are received in that particular location of the observer. By taking the predominant signals on each of these two axes and prolonging the vertical and the horizontal lines passing through them, the observer will obtain several points on the topographic representation of the region covered which will indicate the instantaneous location of the plane over such a region.

The method of correlating the image on the screen 30 of the cathode ray tube 17 with the topographical image of the territory over which the plane flies permits the pilot to determine at once his instantaneous position over said territory. The rapidity and ease of this system is important in the case of fast flying modern planes which are moving at the speed of several miles per minute, the speed to which corresponds to the rapid variations of amplitude of the signals which are visible on the screen of the oscillograph.

My invention is also useful in combination with direction finding means such as a loop or plurality of loops or combination loop antenna systems wherein the sense of direction toward any of the transmitting stations simultaneously received may be directly determined when a plane flies between a plurality of transmitting stations. My invention enables the pilot to easily verify the actual direction of the plane by the use of a simple loop receiver and whether the plane is flying on the line passing through the two stations. It is easily seen that if the loop is disposed longitudinally with the axis of the plane, the signals coming from one station will maintain their maximum of intensity on the screen 30 as long as the plane is directed towards a station. Any deviation or drift is indicated by a decrease of intensity or change in character of the wave form of the visually reproduced signal in that direction. The signals coming from the second station will also show a maximum of intensity independently of the distance with the condition that the plane be directed exactly towards this second station. It results that if

the signals coming one from the station at the starting point and the other from the destination point, simultaneously produce maximum intensities, the pilot is assured that the plane is moving along a line passing through these two stations.

The greatest advantage of a coordinate beam network system such as described is the facility of continuously expanding the covered area in all directions, without interference with previously installed transmitters. The panoramic receiver, however, can be used quite as well with simpler beam network systems which can give just as good indications over certain restricted areas, concerning the progress of flight of a plane. Fig. 38 represents such a system. The usual type of radio range transmitter is located at point O for simultaneously emitting two signals on a frequency F at an angle to each other, such keyed in such a manner as to create the usual paths

A, B, C, D, of equi-potential energy. A series of marker beacon stations are distributed along the paths A, B, C, D, each of these stations emitting signals on frequencies f_1, f_2, f_3, f_4, f_5 , within a band covered by the panoramic receiver carried on board of the plane. Such a panoramic receiver can actually cover two bands of frequencies, as will be shown hereinafter, one band for example in the low frequency range of the radio range beacons, and the other on a much higher frequency of the marker beams.

As the plane travels along the course of the radio range and passes through a succession of marker beams, the observer can locate his exact position. If the frequency variation from marker to marker is proportional to the distance separating them, a map or similitude configuration of the area covered along the range can be used, such as shown in Figs. 10, 11 and 12.

The pilot will be able to maintain the aircraft along one of the courses A, B, C or D defined by the radio range beacon, by keeping the indications of the radio range signals on the screen of the panoramic receiver, and which should appear as the curve C_1 of Fig. 36. In that figure, C_2 shows the signals received off-course with respect to the range, and C_3 when the plane is in a zone substantially on the bisecting line between two courses.

In some applications of my invention, it is important to show two images on the screen of the cathode ray oscillograph in certain relationship to each other, so as to permit the comparison between the signals received. Such may be the case in a radio compass giving simultaneous indications of the direction of various sending stations in a panoramic receiver covering more than one band of frequencies, such as described hereinafter. In a panoramic radio compass, I use two directional loops alternately, one or the other, as shown in Fig. 23, or a combination of a loop and an antenna in which the connections to the loop are alternately reversed as shown in Fig. 21. The images produced with each antenna system are shown on one side or the other of the screen of the oscillograph by periodically reversing the connections to one set of the deflecting plates as shown in Fig. 22. Such reversals of connections from either loop or deflecting plates have to be made in synchronous relation with the variation of capacity of the periodically varying tuning element. I accomplish this by using the same rotating shaft 19 to operate the various switches which complete this reversing of connections. In Figs. 19 and 20, shaft 19

which drives the periodically tuned condensers, is geared to a shaft 112 through gears 110, 111. A cam 113 is carried by shaft 112. This cam is so arranged as to press down the switch arms 115 and 116 during the rotation of 180° of the shaft 112. The gears 110 and 111 have a ratio of 1 to 2. It is thus easily seen that when the shaft 19 rotates during a full revolution, the cam 113 presses down on switch arms 115, 116 and during the next full revolution these switch arms are released. When the switch arms 115, 116 are pressed down, the switch arm 115 makes contact to a fixed contact 118 and switch arm 116 makes a contact with a fixed contact 119. When these switch arms are released, the switch arm 115 makes connection with fixed contact 117 and switch arm 116 makes connection with fixed contact 118. The action of the release of these switch arms is further helped by a repulsion spring 120. This arrangement forms a reversing mechanism which works in conjunction with the rotating shaft 19 so as to reverse the connections to a circuit such as shown in Figs. 21, 22 and 23. In these circuits, reference 121 represents a loop which operates in conjunction with an antenna system 10. One end of this loop is connected to the contacts 117, 119 and the other end is connected to contact 118. The switch arms 115 and 116 are connected to the input of the receiver. It can be seen that by rotating the shaft 19 during one complete revolution, the loop 121 will be connected in one way to the receiver and during the next revolution the connections from this loop will be reversed, thus changing by 180° the phase of the loop, consequently the pattern of reception of the receiver. In order to compare the signals received from these two different patterns of reception, I also reverse, at the same time that the loop connections are reversed, the connections to one set of deflecting elements of the cathode ray oscilloscope 17. This is done exactly at the same moment by using the same cam mechanism 113 according to Fig. 22, with another set of switch arms 122, 123 and contacts 124, 125, 126. In this manner I obtain a perfect synchronism between the rotation of the shaft and consequently the periodical variation of the band pass of the receiver obtained through the rotation of the condensers 3 and 4, and the alternately obtained reception pattern for each revolution of the condensers 3 and 4 and alternate reversing of the image on the set of deflecting plates 15.

Fig. 32 illustrates what happens when I reverse the loop connections such as is shown in Fig. 21. The reception patterns are two cardioid curves which are facing each other as shown in Fig. 32. Stations coming from a very narrow zone A, A', give equally strong signals in each position of the loop. On each side of these zones there are other zones B_L, B_R, and B'_L and B'_R, respectively front and back, in which the signals received in one position are stronger than in the other position and then the zones C and C' in which stations will be received in only one position of the loop and not in the other position. As the signals are produced on one side of the line A—B for one position of the loop and on the other side of the line A—B for the other position of the loop, I obtain on the screen 30 of the oscilloscope 17, two patterns which face each other and are easily compared.

Signals of equal amplitude on both sides of the line come from stations situated in zones A and A'. Signals of unequal amplitude come from the 75

other zones. The signals coming from zone C or C' will give signals on only one side or the other side of this line. This enables the observer to tell at once the direction of each station which is simultaneously received on the screen 30 of the oscilloscope 17. This reference is still facilitated in an arrangement which allows the screen 30 of the oscilloscope 17 to be adjusted in an angular relation with the loop 121. This is shown in Fig. 30.

Referring to Fig. 30, a hand wheel 137 serves to simultaneously rotate both loop 121 and cathode ray oscilloscope 17 over an angle of 180°. This is accomplished through the linking elements 130, 131, 132, 133, including pulleys and gears. The oscilloscope is enclosed within a shield 138 which rotates in a sleeve 139. The connections to this cathode ray oscilloscope are brought to flexible wires and cable 140. In a preferred arrangement, the line A—B of the screen of the oscilloscope points up and down when the equi-signal zone A, A' extends straight in front of and behind the plane. As the observer rotates the loop so as to bring the equi-signal zone A, A' by a certain number of degrees to the left, or to the right of the plane, the screen 30 is rotated so that the line A—B makes an equal number of degrees with the vertical line which can be read on the calibrated scale. The calibrated scale is shown at 141 in Fig. 31a, Fig. 31b, Fig. 31c, Fig. 31d, and Fig. 31e, graduated in degrees and appears adjacent the face of the oscilloscope which permits the observer to read the degree of rotation of the oscilloscope which corresponds to the degree of rotation of the loop 121. By referring again to Fig. 31a, Fig. 31b, Fig. 31c, Fig. 31d, Fig. 31e, it can be seen how with such an arrangement the observer can instantly tell for each station the direction of the incoming signal simultaneously. I have shown in these figures a series of signals coming from four different stations, one in each cardinal point of the compass. These figures show how each of these stations change their pattern on the screen of the oscilloscope as the loop is swung and the oscilloscope moved 45° to right and to the left and then 90° to right and to the left. It can be seen that the observer can definitely determine the direction of each of the stations with respect to the axis of the aircraft.

From these figures it can be seen that it is very easy to determine when the aircraft is passing through a plane connecting two distant stations and the angular relationship between that plane and the flying direction of the aircraft. Such information can greatly facilitate cross-country flying by using any appropriate signals, such as from broadcasting stations, as a source of information. In Fig. 33 I give such an example.

A pilot who wishes to fly from Washington, D. C., towards Scranton, Pa., will tune in on the panoramic receiver a plurality of stations such as, Washington, Baltimore, Philadelphia, New York, Pittsburgh, Atlantic City, Cleveland, and Buffalo, indicated in Fig. 33. The plane will frequently pass through various regions such as 1, 2, 3, 4, 5, 6, 7 and 8, during which he simultaneously receives equi-potential signals on both sides of the screen 30, corresponding to two stations, which are at the moment in the same plane. The pilot is enabled to determine the angular relation of that plane with the direction of movement of the aircraft. This definitely indicates to the pilot the progress of flight of the plane and

the actual location. The observer will thus be able to take fast bearings which will permit him to make corrections of the course of the plane which may be necessary on account of drift due to cross-wind. The pilot will be able to change his direction at any definite point along the course to follow another direction if he wishes to do so.

Fig. 23 represents a similar arrangement to Fig. 21 in which instead of using loop 121 and antenna 10, we are using two loops, 142, 143, at an angle to each other. With a compass switching arrangement similar to the one described in Fig. 19 and Fig. 20, a cam mechanism 113 acts upon a spring 144 which alternately closes contacts 145 or 146 so as to alternately change the loop for every rotation of our shaft 19. The signals received on one loop or the other are formed on one side or the other of our line A-B on the screen 30 on the oscillosograph 17 so as to obtain two symmetrical curves which give us by comparing them, the necessary information as to the direction of each station received.

Another form of compass embodying my invention is shown in Figs. 34 and 35. The direction of each station among a plurality of stations is visually shown by reproducing each of said stations, inclined to one side or the other according to the side from which the signal arrives. I obtain this result by the use of a radio receiver which can give a positive or negative potential indication in its output from each of the stations received, according to its direction, and superimposing these successively received potentials in the continuously varying sweep voltage, so as to slow down or increase the rate of speed of the cathode ray beam, as we are passing through the various signals. A positive potential applied to the cathode ray beam will increase the speed of that beam during the short time period when such a potential is applied and the signal appearing on the screen will look like a "saw tooth" inclined for example to the right, as indicated in Fig. 35. In Fig. 34 I show two radio frequency energy collecting means, that is, loop 160 whose plane is perpendicular to the direction of flight of the plane, and a non-directional antenna 10. Each of the two circuits of these energy collectors are similarly tuned by means of condensers 1, 3, 5 and 1a, 3a and 5a. A common oscillator 161 is used for separately heterodyning the two signals. This oscillator is tuned by means of condensers 2, 4, 6. The relationship between all these condensers is the same as in Fig. 1, already described, only three condensers are ganged together instead of two: 1, 1a, 2, also 5, 5a, 6, and also 3, 3a, 4, the latter group being continuously rotated by means of motor 18. The signals separately converted into strictly the same intermediate frequency in the converting tubes 162 and 163 are further amplified respectively through transformers 164 and 165 and tubes 166 and 167. The output from the loop is brought to intermediate frequency transformer 168 which has a secondary tapped in the center. The signal energy is introduced from the circuit connected with antenna 10, through condenser 170 and center tap lead 168a from the transformer 169. These signals arrive at a phase angle depending on the direction of the station with relation to the loop. The combined signals are fed in a double diode rectifier 171 shunted by a balancing resistor 172 and bypassed by condensers 173 and 174.

It can be seen that the two signals arriving through antenna 10 and loop 160 are received at different phase angles and that on one diode 171a, the sum of the two vectors is applied whereas on the other diode 171b, the difference of the vectors is applied. According to which side gives the greater signal, there will be obtained at the ends of resistance 172 a series of differences of potential and if one end is grounded, the other end may be either positive or negative with respect to ground. This other end is connected to the plate 9b of the oscillosograph, plate 9a being connected in the usual manner to the synchronized sweep voltage. The signal from the antenna is separately detected and amplified in tubes 175 and 176, its output being applied to plate 15 of the oscillosograph. The horizontal sweep voltage for the cathode ray beam is now submitted to the combined voltage of the charged condenser 21 and the positive or negative potentials applied to the other plate, so that this beam will be accelerated or decelerated as the set is tuned through certain stations. By referring to Fig. 35, it will be seen how a signal will appear on the screen. If it comes from straight ahead, where the loop does not receive any signal, the station will appear on the oscillosograph as in curve A1, if the plane turns for example to the right, so that a negative voltage is applied to the sweep control circuit while the receiver tunes through that station, the curve will incline to the left as in A2 and if the plane turns to the left, a positive voltage will be applied which will incline the curve as shown in A3. Each station will appear straight or inclined to one side or the other side, according to the side from which the signal arrives, and this inclination will be proportion to the phase angle difference between the two signals and to the amplification of the signal applied on plate 9b.

For many purposes it may be necessary for two different bands of frequencies to be observed at the same time, such as long waves for radio range beacons, and short waves for marker beacons. It may also be desirable to inspect a frequency range which cannot be covered by one coil and condenser passing from maximum to minimum.

My panoramic receiver can be made to cover such widely different bands by periodically switching from one band to another and representing each one of these bands on a different portion of the screen, such as the top and bottom line of one of the axes such as shown in the diagram illustrated in Fig. 37. In this diagram, an antenna 10 is shown coupled to either of two coils 150 or 151 which are connected to grid 11 of tube 12. These coils can be tuned by condensers 1 and 1a. The circuits through coils 150 and 151 return to ground, through the leads 152 and 153 and switch 154. I provide condensers 2 and 2a connected in parallel with the condensers 1 and 1a through the leads 155-156 and the switch 157 to one side of the continuously rotating condenser 3. The switches 154-157 operate simultaneously by means of a cam arrangement such as shown in Fig. 19, and it can be seen that for each 360° rotation of the condenser 3, coils 150 or 151 are successively connected to ground and operative, while the rotating condenser 3 is connected to the respectively operating circuit. It can also be seen that each circuit can be individually tuned within limits set by condensers 1 or 1a and the band of frequencies

swept in each circuit can be narrowed or widened by the setting of condensers 2 or 2a. By an arrangement similar to the one shown in Fig. 22, I may cause switch 158-159 to operate synchronously with 154-157 so as to reverse the connections to the vertical deflecting plates 15A or 15B, for each change of coils 150-151. In this manner, two sets of images are reproduced on each side of the horizontal line of the oscillograph screen, each image corresponding to the band of frequencies swept. Instead of using an arrangement such as shown in Fig. 22, I may employ an arrangement in which the two axes are used alternately, as in Fig. 28.

When a multiplicity of stations are seen on the screen 30 of the oscillograph 17, the observer can determine the frequency of each station in different ways such as will be described below.

With reference to Fig. 18, a high frequency generator OSC which may be calibrated both in frequency and in output power, is coupled to the input circuit of a panoramic receiver shown diagrammatically in simplified form. A signal produced by the signal generator will appear on the screen of the panoramic receiver and by referring to the frequency calibration of this generator, an observer is able to determine the band limits covered by the panoramic receiver. It is also easy to determine the frequency of any of the signals received on the panoramic receiver by adjusting the signal generator so as to superimpose the two signals on the screen, and reading the frequency corresponding to that adjustment. It is also possible to measure the amplitude of each signal received, by comparing the amplitude of said signal with an equal amplitude adjacent signal produced by the signal strength calibrated generator.

It may be important to be able to listen to one of the stations thus received on screen 30 without disturbing the reception of the others. One of my preferred methods is to combine a panoramic receiver with the usual type of receiver in such a way that the periodically tuned circuit creates visual signals on the screen 30 of the oscillograph 17, whereas a separately tuned receiving system gives an aural indication of any one of the signals received and is so linked with the panoramic system as to cause a visual indication on the screen of the oscillograph which permits visually reproduced stations to be identified with the stations to which the observer is listening. In Fig. 17 the antenna circuit 10 is inductively coupled to such a receiving circuit, the latter preferably containing a regenerative stage. When this stage is in the state of oscillation and if the condenser 1a is properly tuned, there will be a locally generated signal coming from the oscillating stage which will appear on the screen 30 of the oscillograph 17 in a position corresponding to the frequency for which condenser 1a is tuned. This signal will move to the right or to the left on the screen according to the position of the condenser 1a, and can be made to coincide with any of the other signals appearing on the screen. In that moment the receiver is tuned exactly in the same frequency as the signal with which it coincides on the screen, and the observer can listen to that station aurally in the output of that receiver. The condenser 1a can be actually calibrated in frequencies and the observer knows at a glance the frequency of any of the plurality of signals received visually on the screen 30 by referring to this calibration. If aural reception is not needed, a simple cali-

brated oscillator in the place of a regenerative receiver for the same purpose and with the same effect may be used as shown in Fig. 18.

There are other ways in which I can identify this station and have aural reception simultaneously with the visual reception. In a more complicated receiver, I use a superheterodyne receiver in connection with the panoramic receiver and use the variable oscillator of the latter superheterodyne to impress upon the screen of the panoramic receiver a signal which will vary in position according to the position of its tuning elements. As the frequency of such an oscillator is generally higher than the frequency of the signal received by a difference equal to the frequency of the intermediate frequency amplifier, this signal will not actually coincide with the signal to which the observer is listening. In order to do so, it is necessary to use a separate fixed oscillator of the same frequency as that of the intermediate frequency amplifier and heterodyne it with the signal from the oscillator of the superheterodyne receiver and then impress the resulting signal on the antenna circuit of the panoramic receiver. That signal will coincide with the signal desired.

In mobile installations where the source of energy for the radio receiver comes from batteries such as seen in Fig. 24, it is not necessary to use a special motor for rotating the shaft 19. The same motor-generator set which is used for producing the high voltage necessary for the various circuits of the receiver can be mechanically coupled to the shaft 19 which creates the periodic frequency variation required by the panoramic receiver through the rotation of condensers 3 and 4 and also the necessary sweep voltage from condenser 21.

While I have described my invention in certain preferred embodiments, I realize that my invention is capable of many applications and modifications not mentioned herein. For example, in field surveys for determining the possible location of broadcast stations where frequency allotments by the Federal Communications Commission are becoming so difficult and restricted, the system of my invention is particularly useful. The panoramic receiving system of my invention set up in a proposed broadcast station location, enables an accurate determination to be made of the possible interference on particular frequencies to be expected at the site of a proposed station, thereby enabling an allocation engineer to determine the merits of various frequencies for the proposed station site. Such a frequency analyzer is particularly useful in presenting testimony in evidence with respect to such allocations before the Federal Communications Commission.

Other applications of my invention will be apparent and no limitations upon my invention are intended other than may be imposed by the scope of the appended claims.

What I claim as new and desire to secure by Letters Patent of the United States is as follows:

1. In a signal receiving system, a signal receiving circuit, means for periodically tuning said signal receiving circuit over a selected band of frequencies, detector and amplifying circuits connected with the aforesaid circuit, a cathode ray oscillograph including a cathode ray beam generator and two sets of deflecting elements, and means operative in synchronism with said aforesaid means for selectively and alternately controlling the connection of each of said

sets of deflecting elements with said amplifying circuit.

2. In a signal receiving system for analyzing a plurality of signals, a signal receiving circuit, means for periodically tuning said signal receiving circuit over a predetermined band of frequencies, a cathode ray oscillograph including a cathode ray beam generator and two sets of deflecting elements, means synchronously operated with the first mentioned means for creating a deflecting voltage, and means operative in synchronism with both the aforesaid means for selectively and alternately controlling the connections of each of said sets of deflecting plates with the said signal receiving circuit and with the said source of deflecting voltage.

3. In a signal receiving system, including a signal receiving circuit and means for periodically tuning said signal receiving circuit over a selected band of frequencies, a cathode ray oscillograph including a cathode ray beam generator and two sets of deflecting elements, a source of deflecting voltage synchronously controlled with the said first means, means for alternately connecting each of said sets of deflecting elements with said signal receiving circuit while the other set of deflecting elements is connected with the said source of deflecting voltage, and means for controlling the operation of the last said means in timed relation with the first mentioned means.

4. In a signal receiving system, including a signal receiving circuit and means for periodically tuning said signal receiving circuit over a selected band of frequencies, a cathode ray oscillograph including a cathode ray beam generator and two sets of deflecting elements, a source of deflecting voltage synchronously controlled with the said first means, connections between said source of deflecting voltage and one set of deflecting elements, connections between said signal receiving circuit and the second set of deflecting elements, and means operative in synchronism with the first said means for alternately reversing the connections to one set of said deflecting elements.

5. In a radio receiving system, a pair of radio frequency energy collectors of different characteristic connected through a commutator to a signal receiving circuit including a tuned circuit, means for periodically tuning said tuned circuit over a predetermined band of frequencies, means for operating the said means in synchronism with said commutator so as to alternately change the reception pattern of the signals received during successive periods of operation of said tuning means, a cathode ray oscillograph including a cathode ray beam generator and two sets of deflecting elements, a source of deflecting voltage synchronized with the operation of the first said means, means for connecting one of said sets of deflecting elements to said source of deflecting voltage, and means for connecting the other set of said deflecting elements to the said signal receiving circuit; said system being operable to produce two sets of images on the oscillograph corresponding to the two different resulting reception patterns.

6. In a radio receiving system, a signal receiving circuit, two tuned circuits of different characteristic, means for alternately tuning said tuned circuits periodically over different predetermined bands of frequency, means operative in timed relation with the first said means to alternately connect said tuned circuits to said

signal receiving circuit, a cathode ray oscillograph including cathode ray deflecting elements substantially normal to each other, one of said elements being connected with said signal receiving circuit, a source of deflecting voltage operative in synchronism with the first mentioned means, another of said deflecting elements being connected with said source, and means operative in synchronism with the second said means for interchanging the connections of said deflecting elements for producing separate images along two lines normal to each other and corresponding to the signals received through each of the two tuned circuits.

7. In a radio receiving system, two input circuits of different characteristic, a receiving circuit, means for periodically tuning said receiving circuit, means operative in timed relation with the first said means to alternately connect each of said input circuits to said receiving circuit, a cathode ray oscillograph having two sets of deflecting elements, a source of deflecting voltage operative in synchronism with the first mentioned means, connections between said source and one of said sets of deflecting plates, and means operative in synchronism with both the aforesaid means for alternately connecting the other of said sets of deflecting plates with said receiving circuit in different phase relations.

8. In a signal receiving system, a signal receiving circuit, means for periodically tuning said signal receiving circuit over a predetermined band of frequencies, a cathode ray oscillograph, sets of deflecting elements associated with said cathode ray oscillograph, a source of deflecting voltage operative in synchronism with the first said means and connected with one set of said deflecting elements, connections between said signal receiving circuit and another set of said deflecting elements, and means for synchronously operating said tuning means and reversing the said connections of the last mentioned set of said deflecting elements with respect to said signal receiving circuit.

9. A signal receiving system comprising a signal receiving circuit, means for periodically tuning said signal receiving circuit over a predetermined band of frequencies, a cathode ray oscillograph including coacting sets of deflecting elements, a source of deflecting voltage operative in synchronism with the first said means and connected with one set of said deflecting elements, connections between said signal receiving circuit and another set of said deflecting elements, means for successively reversing said connections of the last mentioned set of deflecting elements with respect to said signal receiving circuit, and means for synchronously operating the said last means in timed relation with said periodic tuning means.

10. In a signal receiving system, a pair of radio frequency energy collecting circuits having different characteristics, a signal receiving circuit, means for periodically tuning said signal receiving circuit over a predetermined band of frequencies, an oscillograph including a set of deflecting elements reversibly connectible with said signal receiving circuit, a source of deflecting voltage operative in synchronism with the first said means, another set of deflecting elements connected with said source, means for alternately connecting the first mentioned set of deflecting elements with said signal receiving circuit in opposite phase relations in synchronism with said tuning means, and means for synchronously

connecting said signal receiving circuit with either of said radio frequency energy collecting circuits in timed relation to the operation of said periodic tuning means and the last said connecting means.

11. In a signal receiving system, a signal receiving circuit, an oscillograph having two sets of deflecting elements, a source of sweep voltage connected to one of said sets of deflecting elements, means for connecting the other set of deflecting elements to said signal receiving circuit, an electron tube circuit interconnected between said signal receiving circuit and the said source of sweep voltage and controlled by said source for periodically tuning the said signal receiving circuit over a predetermined band of frequencies in synchronism with said sweep voltage by the variation of the dynamic characteristics of said electron tube circuit.

12. A direction finder system comprising in combination, an angularly shiftable direction finder antenna, a signal receiving circuit connected therewith, means for periodically tuning said signal receiving circuit over a predetermined band of frequencies, an oscillograph connected with said signal receiving circuit, for visually reproducing signals received, deflection control circuits for said oscillograph, means for controlling the operative relationship of said control circuits with respect to signals received by said signal receiving circuit in timed relation to the operation of said periodically tuning means, and means for angularly rotating the oscillograph about its central axis in angular relation to the movement of said direction finder antenna.

13. In a direction finder system, an angularly shiftable direction finder antenna, a signal receiving circuit connected therewith, means for periodically tuning said signal receiving circuit over a selected band of frequencies, an oscillograph connected with said signal receiving circuit for visually reproducing signals received, sweep circuit control means for said oscillograph, means for mounting said oscillograph for rotation on an axis substantially normal to the viewing screen thereof, means for synchronously controlling said control means in timed relation to the operation of said periodically tuning means, and means for rotating said oscillograph about the axis thereof in angular relation to the movement of said direction finder antenna.

14. In a system of navigation including a plurality of signal transmitting stations of different frequency characteristics, a multiple frequency signal receiving apparatus adapted to be carried by a mobile body operative along a given course in geographic relation to said signal transmitting stations, indicator means connected with said signal receiving apparatus including an oscillograph operative to visually and simultaneously reproduce in spaced relationship according to their frequency a plurality of signals from said signal transmitting stations in different amplitudes on the screen of said oscillograph, a band bearing a topographic representation of the area with respect to which said mobile body is movable, and means for variably positioning said band with respect to the screen of the oscillograph for aligning the signals reproduced in different amplitudes on the screen of the oscillograph with the topographic representation carried by the band and indicating by the amplitude relationship of said signals the location of the mobile body along said course over the geo-

graphic area with respect to which the mobile body moves.

15. A signal receiving system comprising a radio frequency energy collecting circuit, signal receiving circuits connected with said energy collecting circuit, means for periodically tuning one of said signal receiving circuits over a selected frequency band, and an oscillograph connected with the one said signal receiving circuit for visually reproducing signals received thereby, sweep circuit control means associated with said oscillograph, means synchronously operating said control means and said periodically operated tuning means for simultaneously and visually reproducing a plurality of signals received from spatially displaced sources and included in said selected frequency band, a signal receiver coupled to the other of said signal receiving circuits, an audible responsive device connected with said signal receiver, means for independently tuning said last mentioned signal receiving circuit to selected frequencies within the frequency band over which the said first mentioned signal receiving circuit is periodically tuned, and means for generating locally in said signal receiver an oscillating signal whose frequency is controlled by said independent tuning means, said locally generated oscillating signal being transmitted through said signal receiving circuits and reproduced on said oscillograph as an indication of the frequency to which said last mentioned signal receiving circuit is tuned.

16. In a signal receiving system, a radio frequency energy collecting circuit, a signal receiving circuit connected therewith, an oscillograph connected with said signal receiving circuit for visually reproducing signals received therethrough, sweep circuit control means for said oscillograph, an audible responsive device connected with said signal receiving circuit, tuning means connected with said signal receiving circuit and adjustable for selectively tuning said signal receiving circuit to any one of a plurality of individual frequencies, means connectible with the control means of said oscillograph for periodically tuning said signal receiving circuit through a predetermined tuning range thereof and synchronously operating said control means of said oscillograph for simultaneously reproducing on said oscillograph a plurality of the signals at the frequencies receivable over the said tuning range of said receiving circuit, and means for interrupting the operation of said periodically operated tuning means for observing the audible response of any one of the selected frequencies visually reproduced on said oscillograph.

17. In a signal receiving system, including two energy collecting elements of different directional characteristics, each of said elements being followed by an independent receiving channel, means for periodically tuning said receiving system over a selected frequency band, means for combining with the output of one of said channels the signals of the other channel so as to obtain a series of positive and negative impulses according to the phase of the signals received in the two said directional energy collecting elements, a cathode ray oscillograph including two sets of deflection control elements, means for periodically controlling one set of said elements in synchronism with the periodical tuning of the said receiving system, means for simultaneously impressing on the same set of control elements the said series of positive and negative impulses

so as to accelerate or retard the movement of the cathode ray beam of said oscillograph, and means to impress on the other set of control elements the output signals of said receiving system.

18. In a signal receiving system, including a combination of a directional and a non-directional antenna, means for periodically tuning said receiving system over a selected frequency band, means for producing in said receiving system a series of positive and negative potentials according to the signals received with respect to the said combination of antennae, a cathode ray oscillograph including two sets of deflection control elements, means for periodically controlling one set of said elements in synchronism with the periodical tuning of the said receiving system, means for simultaneously impressing on the same set of control elements the said series of positive and negative potentials, and means to impress on the other set of control elements the amplified output signals of said receiving system from one of said antennae.

19. In a radio receiving system two periodically tuned circuits each of these circuits being tuned over a different band of the frequency spectrum, means operating synchronously with said periodically tuned circuits for periodically and successively connecting each of said circuits into the receiving system, a cathode ray oscillograph having a viewing screen and two sets of deflecting elements, means synchronously operated with the first mentioned means for creating a deflecting voltage, and means operative in synchronism with both the aforesaid means for selectively and alternately controlling the connections of each of said sets of deflecting plates with the said signal receiving circuit and with the said source of deflecting voltage.

20. In a radio receiving system, including a periodically varying tuning element, two reactances, a commutator operated in synchronism with said tuning element to successively connect said reactances, to the periodically varying element so as to periodically and successively tune said receiving system over different ranges of the frequency spectrum, a cathode ray oscillograph having deflecting elements and a viewing screen for visually reproducing signals received in the respective frequency ranges, a pulsating current generator operating in synchronism with said commutator, a plurality of deflecting circuits including said pulsating current generator for controlling the position of said visually reproduced signals on said viewing screen, and means synchronously operative with said commutator and said generator to successively and periodically connect said deflecting circuits to said deflecting elements to reproduce each signal received in the different frequency ranges of the said radio receiving system over different regions of the screen of said cathode ray oscillograph.

21. In a system for determining the location of a mobile body with respect to a plurality of radio beacons, each of said beacons emitting two signals of substantially equal power and of two different frequencies, the combination of said two frequencies from each beacon being characteristic of the particular geographic location of said beacon and determined in accordance with a predetermined function of distance of said beacon from a geographically fixed origin, both of said signals from one and the same beacon being emitted according to similar vector diagrams, and said vector diagrams being at an angle to

each other, a signal receiving apparatus carried by the said mobile body and having means to substantially simultaneously and visually indicate the frequency and amplitude of each of the two signals from each of a plurality of said radio beacons in spaced relation on a display surface, said spacing being indicative of the geographical spacing of the beacons.

22. In a system of navigation, a plurality of radio beacons established in various points on a given geographic area, each beacon emitting two signals of two different frequencies, each of said frequencies being included in a continuous band having predetermined limits and determined for each beacon by the geographic coordinates of said beacon in accordance with a predetermined continuous function of the distance from a geographically fixed origin, a radio signal receiving apparatus mounted on a mobile body and having means including a cathode ray oscillograph with a screen to visually and substantially simultaneously indicate the respective field strength and frequency of the two signals from each of a plurality of said beacons, said frequency indications being spaced on said screen similarly to the spacing between said beacons on said geographic area, and the location of said mobile body with respect to said beacons being determined by the amplitude relationship of the said signals.

23. A radio compass comprising in combination two signal collecting circuits having different directional characteristics, a signal input circuit, amplifying circuits and an output circuit, a cathode ray oscillograph having an observation screen, and synchronous means for periodically and alternately connecting each of said signal collecting circuits to said signal input circuit and for modifying connections between said oscillograph and said output circuit, so that the signals received through each signal collecting circuit appear on a different zone on the observation screen of said oscillograph.

24. In a signal receiving system, a radio frequency energy collecting circuit, a signal receiving circuit having connections to the aforesaid circuit, means for periodically tuning said signal receiving circuit successively to different predetermined frequencies, a cathode ray oscillograph including a beam deflecting system, a source of deflecting voltage operative in synchronism with the first said means, connections between said signal receiving circuit and said deflecting system, and means for synchronously reversing the connections between the deflecting system and the signal receiving circuit and the connections between said signal receiving circuit and said radio frequency energy collecting circuit in timed relation to the operation of said periodic tuning means.

25. The method of navigating along a line with the aid of a plurality of radio beacons and a radio receiver comprising a cathode ray oscillograph having a screen and a calibrated chart adjacent the screen, which includes the steps of distributing a plurality of beacon signals at random points along said line, adjusting the frequency of each of said beacons so that the difference of frequency between any of said beacons is made substantially proportional to the geographic distance separating them, monitoring at various positions along said line a continuous band of frequencies including a plurality of the beacon signals, each signal producing a current impulse whose amplitude is characteristic of field strength, separating said impulses as to time by

intervals proportional to the frequency spacing between said signals, producing on said screen visual and substantially simultaneous indications of said current impulses which are characteristic of the relative field strengths of said beacon signals and of the relative distances between said beacons, and controlling the linear separation between said indications on said screen for directly reading on said chart the said distances between beacons.

26. The method of navigation with the aid of a radio beacon emitting from a given point two signals in two different directions and creating thereby in space an equi-potential line of radio frequency energy, and a radio receiver having a cathode ray oscilloscope with a screen and a distance calibrated scale adjacent to that screen, which method includes intersecting the said equi-potential line at different points on the course thereof with other radio signals, adjusting the frequencies of said other radio signals within a given frequency band so that the differences of frequency between any of said signals are substantially proportional to the geographical distances separating them along said line, monitoring at various positions on said line a continuous frequency band including a plurality of said signals, each signal exceeding a certain field strength being observed as a visual signal on said screen simultaneously with but distinctly from others of said signals, and controlling the intervals between said visual signals so as to convert the relative spacing therebetween directly on said chart into geographical distances between said points, the relative amplitudes between said visual signals determining the location of the monitoring position with respect to said points.

27. The method of navigation with the aid of a multiple frequency radio receiver including a cathode ray tube having a screen and a chart calibrated in distance, which includes emitting from each of a plurality of points situated at any convenient location on a given geographic area two signals on two different frequencies, each such combination of two frequencies being determined by one and the same continuous function of the geographic coordinates of the point with respect to two fixed reference axes normal to each other, said signals being oriented according to polar diagrams at substantially right angles with respect to each other but substantially parallel to said reference axes, visually reproducing on said screen the signals from a plurality of said points substantially simultaneously at a position within said area at amplitudes corresponding to the field strength of each signal and in spacial relationship determined by their frequency, and controlling the said spacial relationship between the signals on said screen to correspond with the said distance calibration on said chart, the location of said position with respect to said axes being determined from the relative positions and amplitudes of said signals measured on said chart.

28. In a system of radio navigation, a pair of geographically fixed reference axes and a plurality of stations distributed at random locations with respect to said axes, each of said stations emitting two directional signals on two different frequencies, the orientation of the signals of such stations substantially corresponding to the orientation of said axes, and the frequency of the one and the other signal from each station being a continuous function of the distance from the one and the other of said axes, a radio receiver

carried aboard a mobile body including energy collecting means and a receiving circuit, a cathode ray oscilloscope including a cathode ray generator and a screen, a distance calibrated scale adjacent said screen, means for substantially simultaneously picturing on said screen as individual visual signs the signals from a plurality of such stations, in spacial relationship corresponding to their frequency relationship and amplitude relationship corresponding to their field strength relationship, and means for controlling the said spacial relationship between the said visual signs to correspond with the distance calibration of said scale.

29. In a system of aircraft navigation, a multiplicity of radio beacons each beacon radiating energy on two frequencies, each of said two frequencies being contained in a separate predetermined band of the frequency spectrum, and characterizing the geographic location of the respective beacon by being determined as a continuous function of the distance of the respective beacon from a set of geographically predetermined references, means on an aircraft for receiving the energy radiated from said beacons, a receiving apparatus carried by the aircraft and connected with said means, a circuit included therein for receiving signalling energy from a plurality of said beacons and a separate circuit periodically tuned and continuously responsive to all the frequencies contained in the separate bands of the frequency spectrum, an oscilloscope connected in the output of said receiving apparatus, a distance calibrated scale adjacent said oscilloscope, means for visually and substantially simultaneously reproducing on said oscilloscope a plurality of the signals receivable within said predetermined bands of frequency as individual visual signs distinctive from each other in accordance with their respective frequencies and at amplitudes which vary as a function of their respective field strengths, and means for adjusting the linear intervals between said signs to correspond with the distance calibration of said scale for indicating the position of the aircraft with respect to said set of geographically predetermined references.

30. In a signal receiving system, a cathode ray oscilloscope including a cathode ray generator and a screen, means for controlling the movement of the cathode ray in different directions over said screen; a source of periodically varying voltage connected with said means, for deflecting said cathode ray in one direction; and a signal receiving circuit including a tuned circuit, means connected with said tuned circuit and controlled by said source of periodically varying voltage for varying the resonant frequency of said tuned circuit over a frequency range determined by the amplitude of said voltage, and a connection from said signal receiving circuit to the first said means for deflecting said cathode ray in a different direction, whereby all signals received through said signal receiving circuit throughout said frequency range are substantially simultaneously pictured on said screen in spacial relation characteristic of their respective frequencies and in amplitude relation characteristic of their respective field strengths.

31. In a signal receiving system, a cathode ray oscilloscope including a cathode ray generator, a screen, and means for controlling the movement of the cathode ray over said screen; a source of periodically varying voltage; a signal receiving circuit including a tuned circuit, means connect-

ed with said tuned circuit and controlled by said source of periodically varying voltage for varying the resonant frequency of said tuned circuit over a frequency range determined by the amplitude of said voltage, and a connection from said signal receiving circuit to the first said means for deflecting said cathode ray; and synchronous sweep circuit means connected with the first said means, whereby signals received through said signal receiving circuit throughout said frequency range are substantially simultaneously pictured on said screen in interval and amplitude relationships characteristic of the relative frequencies and field strengths, respectively, of said signals.

32. In a signal receiving system, the combination set forth in claim 31 wherein said tuned circuit includes an adjustable element for determining the position of the said frequency range in the frequency spectrum.

33. In a signal receiving system, a signal receiving circuit, a cathode ray oscilloscope having two sets of deflecting elements, a source of periodically variable current of predetermined waveform connected to one of said sets of deflecting elements, means for connecting the other set of deflecting elements to said signal receiving circuit, and means controlled by said periodically variable current for tuning the said signal receiving circuit over a predetermined band of the frequency spectrum in synchronism with the said periodically variable current.

34. The method of analyzing a band of the radio frequency spectrum with the aid of a radio receiver, a source of periodically varying voltage and a cathode ray tube, which method comprises selecting an elementary portion of the band in said receiver, applying the periodically varying voltage from said source to said receiver to displace the elementary portion of said band in proportion to the varying amplitude of said voltage, the limits defining said band being determined by the maximum displacement of said elementary portion under the influence of said voltage, applying signal impulses delivered by said receiver within said band to said cathode ray tube to deflect the cathode ray in one direction in accordance with the amplitudes of said signal impulses, and applying said periodically varying voltage to said cathode ray tube to deflect the cathode ray in another direction for spacing the deflections due to said signal impulses in proportion to the displacements of the elementary portion of said band at which said signal impulses are delivered from said receiver.

35. In a radio receiving system, a signal receiving apparatus, indicator means connected with

5 said signal receiving apparatus, including a cathode ray oscilloscope having a cathode ray generator and a screen, operative to visually and substantially simultaneously indicate on said screen in spaced relation the signal strength and the frequency of each of a plurality of signals received from independent transmitting stations, means for controlling the spacial relationship of the visual indications of signals of different frequencies according to a predetermined frequency scale, a frequency chart showing the frequencies of the independent transmitting stations disposed in accordance with said predetermined frequency scale, and means for variably positioning said chart with respect to said screen for aligning it with the visual indications appearing thereon and identifying the signals and transmitting stations from the corresponding frequencies shown on said chart.

20 36. A radio receiver for simultaneously indicating the integrated field strength of each of a plurality of radio transmitters in a predetermined frequency band of the order of one megacycle or more, which includes an input circuit and a local oscillator periodically tunable for signals within said predetermined frequency band, a first detector connected with said input circuit and said oscillator, an intermediate frequency amplifier having a frequency range of the order of ten or more kilocycles connected with said first detector, a second detector connected with said amplifier, a cathode ray oscilloscope tube having a cathode ray beam generator and sets of deflecting elements adjacent the normal path of said beam, a source of alternating sweep voltage of a frequency of the order of thirty or more cycles per second comprising a condenser and means including a commutator for periodically charging and discharging said condenser, an amplifier connected between said source and one set of said deflecting elements, a calibrated scale adjacent the sweep path of the cathode ray beam, means for energizing another set of said deflecting elements by signal voltages from said second detector, and means for periodically tuning said oscillator for signals within said predetermined frequency band in synchronism with said sweep voltage, the frequency of said sweep voltage being such as to obtain substantially flickerless representation of all signals received within said predetermined frequency band, and the magnitude of the applied sweep voltage being such as to distribute the signal representations in accordance with the extent of said predetermined frequency band and the calibration of said scale.
